TUBE FOR FLUID OR SEMIFLUID
SUBSTANCES

Charles Felix Georges Sabattier, Paris, France

Application August 10, 1937, Serial No. 158,404
In France August 21, 1936

4 Claims. (Cl. 221—60)

The object of my invention is to provide an improved tube intended to contain fluid or semi-fluid substances, such as pasty substances, oils, pulps, or the like, which will be of lower cost, 5 less heavy and liable to be torn off than the usual similar tubes made of tin or lead. With this aim in view I provide a tube comprising a tubular sheath of a fabric of natural or artificial textile material, waterproofed by sizing, impregnating 10 or metallising, woven in one piece, therefore without a longitudinal seam, and closed at both its ends, the closure at at least one end being obtained by means of a stopper having one or a plurality of ejection orifices for the substance with a closure device of any kind for said orifice or orifices.

It is furthermore advantageous for the outer surface of said sheath to be covered with a protecting coating.

Such a sheath can advantageously be made of 20 dressed cloth to which any desired degree of rigidity can be given.

When there is a stopper at only one end, the other end is closed by simply cementing the walls, by compressing said walls by means of a metallic 25 or like joint, or by applying a metallic or plastic substance.

The stopper or stoppers can be made of plastic material or of metal and fixed by cementing, stamping or by pressing.

30 Preferably, the stopper has two surfaces between which the wall of the tube is peripherally clamped, which clamping is obtained by crimping or by screwing on each other two parts to which the said surfaces respectively belong.

35 On the other hand, in a particular construction of such a tube, the sheath is made of ornamented fabric, in particular of embroidered fabric, which gives the said tubes a stamp of elegance making them worthy of a place in a lady's hand bag.

40 By way of nonlimitative examples, two different embodiments of the connection between the sheath and the stopper have been shown in the accompanying drawing.

45 In said drawing, Figs. 1 and 2 are longitudinal sections along the axis of the tube.

Fig. 3 is a perspective view of a part of the tube

and stopper shown in Fig. 1 and Fig. 4 is a cross-section along line IV—IV of Fig. 3.

In Fig. 1, the stopper 1, which carries a central evacuation channel for the substance, which is closed by a cap 2, has at its periphery a kind of 5 circular U-shaped gutter in which is clamped the end of the sheath 4, the fixing being effected for example by crimping.

In Fig. 2, the stopper comprises two parts 5 and 6 which screw onto each other. The end of the 10 casing 7 is peripherally adjusted on the part 5 and the extreme edge of the sheath is bent down on the outer face of said part 5 which is cup-shaped. The part 6 has a complementary shape so that the end of the sheath 7 is firmly clamped 15 between the parts 5 and 6.

What I claim is:

1. In a small container for fluid or semi-fluid substances, comprising an impervious tubular body closed at both its ends the closure at at least 20 one end consisting in a stopper fluidtightly secured to said tube and provided with at least one ejection orifice, and a closure device for said orifice, said tubular body consisting in a tubular sheath of a waterproofed fabric of textile material woven in one piece, i. e. without a longitudinal seam.

2. In a small container as in claim 1, said tubular body being made of waterproofed dressed cloth externally covered with a protecting coating. 30

3. In a small container as in claim 1, said tubular body being made of embroidered fabric externally covered with a transparent protecting coating.

4. A small container for fluid or semi-fluid substances, comprising a tubular sheath of a waterproofed fabric of textile material woven in one piece, i. e. without a longitudinal seam, closure means at both ends of said tube, said closure means at at least one end consisting in a stopper 40 fluidtightly secured to said tube and provided with at least one ejection orifice and a closure device for said orifice, said stopper comprising two pieces removably screwed one upon the other and provided respectively with clamping surfaces in mutual tight engagement and between which is engaged the edge of the tube wall. 45

CHARLES FELIX GEORGES SABATTIER.
